UNITED STATES PATENT OFFICE.

DANIEL TAYLOR, OF LIVERPOOL, COUNTY OF LANCASTER, ENGLAND.

PILLOW OR BOLSTER FOR SAVING LIFE AT SEA.

SPECIFICATION forming part of Letters Patent No. 426,081, dated April 22, 1890.

Application filed November 29, 1889. Serial No. 331,952. (No model.)

To all whom it may concern:

Be it known that I, DANIEL TAYLOR, engineer, of No. 27 Water Street, Liverpool, in the county of Lancaster, England, have invented 5 a new and useful Improvement in Pillows or Bolsters for Saving Life at Sea; that I have not obtained a patent therefor in any country, and that I do hereby declare the following to be a full, clear, and exact description thereof.

10 My invention consists in an improved device which may be used convertibly as a pillow or bolster and as a life-preserved, and is illustrated in the accompanying drawings, in which—

15 Figure 1 is a perspective view of my improved device when closed and in condition for use as a pillow or bolster. Fig. 2 is a longitudinal section thereof. Fig. 3 is a transverse section on the line III III of Fig. 2. Fig. 20 4 is a view showing the application of the device to the human person for use as a life-preserved. Fig. 5 is a perspective view of a modified construction of my improved device. Fig. 6 illustrates the inclosing of the device 25 in a pillow-slip.

The said pillow or bolster consists of a series of air-tight cells $a a'$, formed of rubber, coated cloth, or like air-proof flexible material. The cells open one into another by passages 30 $b b'$, and are provided with blow-up nozzles and valves $c c'$, of usual construction. $d d'$, represent the outer casing, preferably of water-proof material; and $e e'$, filling of horse-hair, wool, or like material. The two parts 35 of the pillow are hinged together at one end

by flexible material f , and at the other end are provided with buckles and straps g . h are shoulder-straps.

Fig. 5 is a perspective view showing a life-saving pillow or bolster, in which both ends 40 of the two halves are connected by elastic webbing i , so that the apparatus may be slipped into position around the body without having to make any connection.

Fig. 6 is a perspective view of a pillow or 45 bolster under my invention, inclosed in a pillow-slip j .

I claim—

1. As a life-saving pillow or bolster, the combination of two buoyant flexible sections, 50 which are connected and fit together laterally, forming a two-ply pillow or bolster, and which are separable laterally to form a body-encircling life-preserved, substantially as and for the purposes described.

2. As a life-saving pillow or bolster, the combination of two buoyant hollow flexible sections having air-cells and filling material, said sections being connected at the ends and fitting together laterally, forming a two-ply 60 pillow or bolster, and being separable laterally to form a body-encircling life-preserved, substantially as and for the purposes described.

In witness whereof I have hereunto set my 65 hand this 8th day of November, A. D. 1889.

DANIEL TAYLOR.
